Filed Dec. 12, 1956, Ser. No. 627,921

7 Claims. (Cl. 37—43)

This invention relates to an improvement in snow blowers and deals particularly with an apparatus designed for connection with a tractor or truck to clear a path in the snow.

An object of the present invention resides in the provision of a snow blowing device which is useful in removing virtually any type of snow from a roadway. The device is operable with wet snow or with dry snow and acts to remove the snow and to throw it a considerable distance.

A feature of the present invention resides in the particular arrangement of blades which makes the operation possible and practical. In a device of the type described, much depends upon the particular shape of the blades and the arrangement thereof. In the present invention the blades have been suitably arranged and proportioned to produce an extremely effective result.

A further feature of the present invention resides in the shape of the wings which act to direct snow to the blowers. These wings are provided with generally vertical sides which are bent to provide downwardly and inwardly inclined lower edges capable of guiding the snow effectively to the blowers.

A further feature of the present invention lies in the specific manner in which the blades and rotor are mounted. The rotor is mounted in a generally cylindrical enclosure on a shaft having a bearing rearwardly of the enclosure.

A second bearing is located at the forward extremity of the shaft and is supported by a cross member connecting the upper edges of the wings of the device. Thus the rotating parts are effectively supported to provide long years of service.

Another feature of the invention resides in the provision of effective guiding means for the diverging wings that may be adjusted to a preferred angle and hence to an optimum degree for the snow conditions then being encountered by the plow.

A further feature of the present invention lies in the arrangement of the parts forwardly of the rotor housing. The rotor housing or casing extends somewhat above the level of the wings which direct snow into the housing. The cross connecting member between the upper edges of the wings has its undersurface considerably below the upper surface of the rotor housing. As a result the housing will accommodate a depth of snow greater than that actually guided thereto. This provides an air space within the rotor housing which prevents the rotor from becoming clogged with snow and permits continuous operation.

Still another feature of the invention lies in the relative dispositioning of the cross connecting member mentioned in the preceding paragraph with certain horizontal members belonging to the frame structure by which the plow is attached to the forward end of a truck or tractor. By reason of such orientation the reactive forces produced by the snow being plowed are transmitted rearwardly to the vehicle without undue torsional or deflec-

2

tive forces being set up in the intervening parts of the snow plow assemblage. In other words, a structure is produced having a maximum resistance to distortion for the particular mass and configuration of the parts making up the plow assembly. Accordingly, the snow plow constructed in accordance with the teachings of the instant invention is very rigid, yet relatively light as far as its weight is concerned.

These and other objects and novel features of our invention will be more clearly and fully set forth in the following specification and claims.

In the drawings forming a part of the specification:

Figure 1 is a snow plow pictured in perspective exemplifying the invention.

Figure 2 is a rear elevation view of the apparatus with the supporting frame removed.

Figure 3 is a perspective view of the wings and the bottom plate which may be used in conjunction therewith.

Figure 4 is a sectional view through the rotor blades and rotor.

Figure 5 is a front view of the rotor showing the relative positions of the blades in dotted outline.

Figure 6 is a perspective view of a guide wing which assists in maintaining a straighter path of movement.

The snow plow is shown assembled in Figure 1 of the drawings. The back plate 10 of the rotor housing is equipped on opposite sides with a pair of vertically extending angle irons 11 and 12. A triangular frame is provided on each side of the plow, the frame including horizontally extending angle irons 13 and 14 connected to the upper ends of the angle irons 11 and 12, respectively. Angle iron braces 15 and 16 connect the lower ends of the angle irons 11 and 12 with the rear ends of the angle irons 13 and 14. Attaching brackets 17 and 19 are provided at the juncture of the angle irons 13 and 14 and the braces 15 and 16 to simplify the attachment with a tractor or truck.

Braces 20 and 21 extend between the angle member 13 and the brace 15 to reinforce the same. Similar braces 22 and 23 connect the angle member 14 and the brace 16. Rearwardly and upwardly inclined braces 24 and 25 are connected to the braces 15 and 16 and the angle members 13 and 14 and project above the angle member 13 and 14. Keyhole-shaped slots or apertures 26 and 27 are provided in these upper ends of the braces 24 and 25 to accommodate a chain yoke which serves to elevate the forward end of the plow by attachment to a suitable hydraulic cylinder or other lift device usually found on many tractors. In lifting, the plow hinges about the brackets 17 and 19 which may be apertured transversely as indicated at 29 and 30. The frame members or angle irons 13 and 14 are held in properly spaced relation by crossed diagonal braces 31 and 32. A cross brace 33 also connects the angle members 13 and 14 and supports an upwardly extending pair of frame members 34 and 35 which are connected together at a point 36 well above their point of connection with the cross brace 33 and one of which extends above the level of the other 30 and is apertured as indicated at 37. This frame member 35 is designed to support a closure operating shaft 39 extending with a transversely bent end 40 by means of which the shaft 39 may be rotated.

The back plate 10 of the rotor housing is generally circular in outline as is indicated in Figures 1, 2 and 5. As is indicated in Figure 5, a peripheral band 41 is connected along the periphery of the plate 10 from a point 42 which is at an angle of about 60° from a vertical plane through the rotor shaft or center of the plate 10 to a point 43 which is approximately 30° above a horizontal plane through the rotor shaft. The back plate 10 is also provided with a peripheral band 44 extending

from a point 45 about 30° from the horizontal plane through the rotor shaft to a point 46 about 15° from a vertical plane through the rotor shaft. Deflector doors 47 and 49 complete the periphery of the overall rotor housing.

The door 47 is hinged at 50 along its lower edge and swings from a position in which the upper edge 51 of the door engages the point 45 of the peripheral band 44 to a position inclining upwardly and to the left of the position shown to form, in effect, a continuous approximate tangent to the casing periphery at the point 42. In the same manner the door 49 is hinged at 52 to the edge 46 of the band 44 and its other extremity or free end 53 swings from a position in contact with the edge 43 of the band 41 to an open position forming, in effect, a continuation of the band 44 from the point 46.

The forward side of the rotor casing is generally open except for a generally crescent-shaped closure plate 54 extending along the upper edge of the housing. This plate 54 is shown in Figure 4 of the drawings and the lower edge 55 of this plate extends somewhat below the outer periphery of the rotor as will be later described.

A pair of wings 56 and 57 extend forwardly from the rotor housing to guide snow into the forward end of the same. These wings are provided with vertical panels 59 and 60 which are bent at points spaced from their lower extremities to form downwardly and inwardly inclined panel portions 61 and 62. Flanges 63 and 64 may be provided extending along the lower edges of the inclined portions 61 and 62 to serve as points of attachment with a bottom plate 65 if it is so desired. The bottom plate 65 and the flanges 63 and 64 are apertured to accommodate bolts such as 66 to attach the plate 65 between the lower edges of the wings 56 and 57. Outwardly turned horizontal flanges 67 and 69 are provided on the upper edges of the vertical portions 59 and 60 of the wings 56 and 57. The flanges 67 and 69 serve to support a channel member or beam 70 in a transverse manner, the arrangement being such that its base 71 is in a vertical plane and its parallel flanges 72 are horizontal. It is to be noted that the lower flange resides in the same horizontal plane as do the angle irons 13 and 14. Due to the correspondence in elevation between the member 70 and the elements 13 and 14, reactive forces from the member 70 are effectively transmitted rearwardly to the vehicle to which the snow plow is attached. An upwardly curved shield 73 extends between the beam 70 and the crescent-shaped plate 54 on the forward side of the rotor housing. This rounded shield 73 is supported by arcuate supporting bars 74 and 75 on the beam 70 and the plate 54, respectively. Thus, the reactive forces referred to above pass through this shield and the rotor casing or housing by virtue of the interpositioning of the shield.

As is indicated in the drawings, the wings 56 and 57 are reinforced by reinforcing plates 76 which extend downwardly from the top flanges 67 and 69 of the wings and which extend along the outer surface of the inclined portions 61 and 62 of the wings, the reinforcing plates tapering toward the bottom edge. Additional reinforcing braces 77 may extend from the plates 76 to the inclined portions 61 and 62 of the wings to further reinforce the same structurally.

A bearing 79 is provided on the rear side of the plate 10 and coaxial with the rotor housing. A rotor 80 is mounted upon a hub 81 extending through the bearing 79. The hub 81 is mounted upon a rotor shaft 82 to rotate in unison therewith. A second bearing 83 is supported by a supporting bracket 84 on the under side of the cross beam 70. The shaft 82 extends through the bearing 83 and is further supported thereby.

The rotor 80 is formed, as illustrated in Figures 4 and 5 of the drawings. The rotor includes a rectangular plate 85 which is secured to the hub 81 on a plane normal to the axis of the hub. Four vanes 86 are secured to the plate 85 to extend toward the corners thereof and usually

slightly beyond. The vanes are of full width for a distance from their outer periphery toward the hub and then are cut to incline inwardly as indicated at 87 to the end of the hub 81. Thus the vanes 86 are substantially wider at their outer periphery than at their inner ends.

Three rotating blades are secured to the shaft 82 to rotate in unison therewith. These blades are angled somewhat similar to the shaping of a propeller blade and act to force the snow toward the rotor. The rotor blade 89 includes a hub 90 and two opposed blades 91 extending radially from the hub in opposite directions. As is indicated in Figure 5 of the drawings, the blades 91 are smaller in radius than the blades 86 of the rotor 80 and are arranged at approximately 30° from the blades 86 and in advance thereof. Considering that the rotor rotates in the direction of the arrow in Figure 5, the blades 91 of the rotor blade 89 are shown as being 30° forwardly of two of the blades 86 of the rotor 80.

A second rotor blade structure 92 is supported upon the shaft 82 forwardly of the rotor blade 89. The rotor blade 92 has a hub 93 and oppositely disposed blades 94 extending at right angles to the blades 91.

A third rotor blade device 95 is mounted upon the shaft 82 forwardly of the bearing 83 and includes a hub 96 and oppositely directed blades 97 which are parallel to the blades 91 of the rotor blade device 89. The radius of the blades 97 is less than that of the blades 94 and the blades 94 are preferably approximately the same length or slightly shorter than the blades 91.

The deflecting doors of the apparatus are operated by the mechanism best illustrated in Figures 1 and 2 of the drawings. A link 99 is pivotally connected at 100 near the free edge of the deflector door 49 and a similar link 101 is pivoted at 102 to the other door 47 near the free edge thereof. The links 99 and 101 are pivotally connected at 103 to a lever 104 which is pivoted at 105 to the rotor casing plate 10. A connecting rod 106 is pivotally connected to the lever 104 at 107. This connecting rod 106 is connected to a crank pin 109 of a crank 110 which is rotatable about a fixed pivot 111. The crank 110 is so arranged that the connecting rod 106 may extend in substantial alignment with the crank in either of two extreme positions of the lever 104.

A universal joint 112 connects the axis of the crank 110 to the operating shaft 39. Thus, by rotation of the operating shaft 39, the crank 110 may be rotated through approximately 180° . This action moves the lever 104 from a position in which the door 47 is closed and the door 49 is open to a second extreme position in which the door 49 is closed and the door 47 is open. Thus the two doors are simultaneously operated between open and closed positions and in each position the connecting rod 106 is approximately aligned with the crank 110 so as to effectively withstand strain upon the doors, tending to pivot them in another position.

As indicated in Figures 2 and 6 of the drawings, a guide plate 113 is pivotally connected along a vertical axis 114 to the forward edge of one or both of the wings 56 and 57. In Figure 6 of the drawings the plate 113 is shown as including an angle bracket 115 which is apertured to fit over a pivot pin 116 on the wing flange 67. Figure 2 of the drawings discloses separable hinge elements 117 which are engaged when the guide plate is in place. An arm 119 is provided on each wing 113 and the arm is provided with a clamping bolt 120 which is engageable through a slot 121 in the cooperable wing flange such as 67. The guide plate may be held in a desired acute angular relation to the wing by the bolt 120 and is in this way rendered most effective as far as steering is concerned for the particular snow conditions currently being encountered. It will be understood that by mounting the plate 113 so that it projects generally rearwardly, it is not subjected to the severe deflective forces that would be experienced if it projected forwardly as in certain prior art arrangements.

In operation, the shaft 82 is either connected to the power take off mechanism of the truck or to a separate motor mounted upon the framework. The plow-shaped body is pushed along the surface of the ground with the rotor and the blades rotating. The snow is directed into the rotor housing and is thrown by the rotor either through the opening provided by moving the door 47 into open position or provided by moving the door 49 into open position. With the arrangement illustrated the snow will be thrown many feet through the air and scattered over the area.

If the snow is deeper than the wings, it is possible to elevate the wings so that by movement of the tractor a top layer of the snow may be removed and blown to one side. The tractor may then be backed up and moved forward a second time with the plow in substantial surface contact with the ground so as to remove a second layer. Similarly, more than two layers can be removed by appropriate action if circumstances so dictate. The guide plates 113 may be set at an angle to assist in maintaining a straight path of movement.

Where one side of the plow or one wing thereof is subjected to much more force than the other, there is a tendency for the plow to turn. This force may be counteracted at least in part by the guide vanes or plates 113.

In accordance with the patent statutes, we have described the principles of construction and operation of our snow blower, and while we have endeavored to set forth the best embodiment thereof, we desire to have it understood that obvious changes may be made within the scope of the following claims without departing from the spirit of our invention.

We claim:

1. A snow plow including a rotor, a shaft rotatably supporting said rotor, a housing encircling said rotor and having an aperture therein through which snow may be forced, a pair of wings secured to said rotor housing and diverging forwardly and outwardly therefrom, said wings being of a height less than the height of the housing, a shield extending forwardly from said housing, a beam having its ends connected to said wings at a point forwardly of said housing and a portion thereof lying intermediate said ends engaging the forward edge of said shield, said beam having its lower edge substantially below the top of said housing and forming an obstruction forwardly thereof, and said housing having an open front through which snow may be guided from said wings.

2. The construction described in claim 1 and including a bearing supported by the center portion of said beam and suspended beneath said beam and supporting said rotor shaft at a locus beneath the forward edge of said shield.

3. The construction described in claim 1 and including a series of spaced bladed members mounted on said rotor shaft forwardly of said rotor and opposed blades on said bladed members angularly related one to the other, said bladed members residing under said shield, the foremost bladed member being of smaller radius than the remaining bladed members.

4. A snow plow including a rotor, a rotor housing, a pair of wings secured to said housing and extending in diverging relation therefrom, a member extending transversely between intermediate portions of said wings, a horizontal shaft disposed at an elevation lower than said transverse member and extending on an axis longitudinally of and intermediate said secured wings, a triangular frame extending rearwardly from each side of said housing, said frames each including a horizontal member located at substantially the same elevation as said transverse member, a pivot member at the rear end of each frame, and means intermediate the length of each last named horizontal member by means of which the rotor, housing and wings may be pivoted upwardly about said pivot members.

5. The structure described in claim 4 in which the upper edges of said wings are provided with horizontal flanges and said transverse member has its ends secured to said flanges.

6. The structure described in claim 5 including means connecting an intermediate portion of said transverse member to the forward end of said housing.

7. A snow plow including a rotor, a shaft rotatably supporting said rotor, a housing encircling said rotor and having an aperture therein through which snow may be forced, a pair of wings secured to said rotor housing and diverging forwardly and outwardly therefrom, said wings being of a height less than the height of the housing, a beam connecting said wings at a point forwardly of said housing, said beam having its lower edge substantially below the top of said housing and forming an obstruction forwardly thereof, and said housing having an open front through which snow may be guided from said wings.
